ABSTRACT OF THE DISCLOSURE

A full range reformate having an F_1 clear octane number of about 90, and derived from hydrogenative reforming over a platinum on alumina catalyst, is fractionally distilled to separate a heart cut having an IBP of at least 70° C. and EBP below 170° C. Said heart cut is reformed at about 535° C. at about 20 atmospheres H_2 pressure at a H_2 /hydrocarbon mol unit ratio of about 10 at about 3 liquid volumes of hydrocarbon per volume of platinum on alumina catalyst, and the second stage reformate is blended with the bottoms and forecut from the first stage reformate to provide full range gasoline having an F_1 clear octane number above 100. Among multi-step routes toward full range gasoline having F_1 clear octane above 100 using only reforming steps featuring platinum catalyst, this method has advantageously high yield and advantageously low deactivation rate for total platinum inventory.

This invention relates to the use of platinum catalyst for reforming at nonregenerative conditions for the preparation of liquid fuels having an octane number above 100.

For many years technologists have been aware of methods for preparing selected fractions of hydrocarbons having an octane number above 100. For example, concentration of aromatics by fractionation or extraction can provide a fraction having an octane number above 100. Refiners are primarily interested, however, in a full range stabilized gasoline making effective use of the components available in the raw petroleum. Nonregenerative reforming of virgin naphtha over platinum catalyst in the presence of a recycle gas containing a predominant volume of hydrogen has been a preferred route toward upgrading the octane number of virgin naphtha. During many years of industrial improvements for nonregenerative (i.e., operation for periods of more than about 60 days prior to regeneration) reforming over platinum catalyst without resort to expedients such as solvent extraction, the goal of producing full range gasoline having an octane number above 100 F_1 clear has been often sought but never attained in practical and economically attractive operations.

By operating at a relatively low pressure, and even then accepting a correspondingly poor yield of reformate, it is possible to upgrade to desirably high octane number, but such low pressure requires frequent regeneration. The increased investment required and greater operating costs for regeneration of platinum containing catalyst has largely discouraged such reforming operations requiring frequent regeneration.

Although reliance merely upon regenerative reforming over platinum has been a desired goal of petroleum proc-

2

ess engineers, greater economy in producing fuel having an octane number about 100 has previously been attainable by resort to one or more techniques such as solvent extraction, thermal reforming, regenerative reforming, purification of hydrogen, and/or other techniques to supplement reforming over platinum. Desired high octane fuels can also be obtained by increased severity of reforming obtained by increasing temperature, or the acidity of the catalyst or by decreasing pressure or space rate, but these procedures also entail increased incremental costs per barrel of reformate. Various proposals have been made concerning the boiling points of fractions treated at various conditions, but the marginal costs of supplemental fractional distillations have discouraged industrial use of most such experimental procedures.

In the operation of a reformer, it is very advantageous to maintain substantially the same operating conditions throughout a number of months, and to adjust the temperature upwardly to maintain the desired octane number of reformate. The designation of ° F. per barrel of feedstock per pound of catalyst has become a unit indicative of the stability of the catalyst at selected conditions. A corresponding metric unit is ° C/l./g. catalyst, each ° F./bbl./pound of catalyst equalling about 1.59° C./l./g. of catalyst. It is necessary to design the process to permit only a limited increase in temperature from the beginning of a run until regeneration is required.

In accordance with the present invention, a motor fuel having an octane number (F_1 clear) above 100 is prepared by subjecting a virgin naphtha to reforming at conditions providing an octane number of the reformate within the range from about 85 to about 93 F_1 clear octane number, and this reformate is subjected to distillation to prepare a heartcut having the approximately 72–162° C. boiling point range, subjecting such heartcut to the severe reforming hereinafter specified, and blending the thus prepared fuel with the bottoms and forecut from the distillation of the reformate from the first stage of reforming. The thus blended fuel is a stabilized, full range gasoline having an octane number above 100. Inasmuch as the selected heartcut is largely free of those components having the highest tendency to produce coke in the reforming operation, this cut can be readily reformed at the indicated high severity without undue loss of catalyst activity and without necessitating frequent catalyst regeneration.

In preferred practice of the invention, the selected reformate heartcut subjected to further severe reforming is one having an initial boiling point within the range from about 70° C. to about 75° C., whereby normal hexane and lower boiling paraffins are substantially excluded; and an end boiling point in the range from about 160° C. to 170° C., whereby polycyclic hydrocarbons are substantially excluded. The process conditions include: controlling the hydrogen to hydrocarbon unit mol ratio within the range from 3 to 8, wherein the hydrogen purity of the recycled gas is maintained by withdrawing a portion of the effluent gas; controlling the space velocity within the range of 1 to 3 volumes of liquid hydrocarbon per volume of catalyst per hour whereby the capital investment in catalyst is not prohibitive; controlling the pressure of the reforming zone within the range from 15 to 30 atmospheres, whereby operation for periods longer than 60 days between regenerations are feasible; and controlling the temperature within the range from 480°

C. to 550° C., whereby the catalyst stability is maintained throughout a series of regenerations, permitting the ultimate useful life of the platinum catalyst to be adequate.

In the drawings, the figure is a self-explanatory flow sheet.

The invention is further clarified by reference to a plurality of examples illustrating a few of the permissible variables within the broadest concept of the invention.

This naphtha is subjected to reforming over a platinum on alumina catalyst to produce a reformate having an F₁ octane rating of about 90.5. This full range reformate is distilled to separate it into 3 fractions, a forerun containing hydrocarbons having an end boiling point of about 70° C. and heartcut having a boiling point range from 70° C. to 165° C., and a bottoms fraction having an initial boiling point of about 165° C. The characteristics of the full range reformate and three fractions are approximately as follows:

The reforming catalyst employed consists of alumina pellets about 1.6 mm. diameter and about 4 to 5 mm. long, having a platinum content of 0.50%, a packed bulk density of 840 g. per liter, a surface area of 260 m.²/g., a pore volume of 0.40 cc./g., an average pore radius of about 31 angstroms, a crushing strength of 4.4 kg., and an ignition loss at 760° C. of 2.5%.

The 103-163° C. heartcut is subjected to severe non-regenerative reforming over a platinum on alumina catalyst at a temperature of 500° C. at a space rate of one and at a hydrogen to hydrocarbon ratio of 8 to 1. The reformate obtained by such severe reforming is admixed with the forecut and bottoms from the previous distillation, and the blend is a full range gasoline having an octane number above 100.

Examples II-V

A heartcut from a reformate having characteristics resembling the heartcut of Example I was subjected to high

severity reforming to obtain upgraded reformate as indicated in the following table:

As previously explained, the operating conditions permit greater severity, whereby an F_1 clear octane of at least

Bromine Number	0.8	0.8	1.1	1.1
Reid Vapor Press.	1.9	2.7	2.9	3.1

Particular attention is directed to the F_1 clear octanes of 102.6 and 103.8 respectively in Examples IV and V, achieved at yields (vol. percent of heartcut) of 84.74 and 82.01% respectively. Using such heartcut, the severity of reforming required to achieve the high octane is within the range of feasible control. If reforming conditions are excessively mild, as illustrated by the combination of space rate, temperature, etc. of Examples II and III, then the supplemental stage of reforming is inadequate to achieve the desired F_1 clear octane number.

Each product is blended with forecut and bottoms to provide a full range gasoline, as noted:

100 might be achieved by appropriate modification of the conditions employed in Examples II, III and IV.

Said heartcut was subjected to experimental reforming conditions selected to produce accelerated aging of the catalyst, to determine the deactivation rate at two sets of conditions, as follows:

	A	B
°C.	527	510
V/VH space rate	10	10
65 Atm. pressure	20	20
H ₂ /oil ratio	6	6
Initial F_1 clear	99.6	97.4
ΔF ₁ /0.16 m ³ oil/0.45 kg. cat	0.147	0.088

Based upon such data, the deactivation rate for preparing 103.8 octane reformate from said heartcut at 1.7 space rate is calculated to be 0.33 F_1 unit per bbl. (0.16 m³) per pound (0.45 kg.) of catalyst. Such data indicate that deactivation rates, measured as °C./liter/gram of catalyst within the range acceptable for regenerating the catalyst fewer than six times per year (nonregenera-

	Examples			
	II	III	IV	V
C ₅₊ yield from reformate	90.2	89.3	86.3	84.6

F_2 +3 cc. TEL	90.8	91.9	93.2	93.9

tive operation for more than 60 days) are attainable at the 103.8 octane level appropriate for achieving a blend having an F_1 octane number of at least 100.

One basis of such experimental data, it was concluded that the concept of severe reforming of the selected heartcut and thereafter blending the ungraded heartcut with the forerun and bottoms provides an effective method for achieving high octane gasoline.

Example VI

A virgin naphtha is distilled to separate a heartcut having a boiling point range from about 75° C. to about 160° C. This heartcut is mixed with 3 mols of hydrogen and passed at a temperature of 520° C. at a pressure of 15 atmospheres over a platinum on alumina catalyst at a space rate of about one. The reformate thereby produced has an octane rating of about 103 F_1 clear. The forerun and bottoms are separately reformed at conditions milder than required for the heartcut, and the blend with the severely reformed heartcut is a full range gasoline having an F_1 clear octane number of 100.1.

The same virgin naphtha is reformed to provide a reformate having a 93 F_1 clear octane, and the 75-160° C. heartcut is subjected to severe reforming to provide a fraction having an F_1 clear octane of 103, and blended with the forerun and bottoms to provide a blend having an F_1 clear octane number of 100.1. The yield of 100 octane gasoline is greater when the reformate heartcut is subjected to the severe reforming than when the naphtha is subjected to such severe conditions. Moreover, the deactivation rate for the catalyst inventory is more favorable if the full range naphtha is first reformed to the 93 F_1 clear reformate prior to separating the heartcut for severe reforming.

Example VII

A variety of reformates derived from a variety of naphthas are evaluated to estimate the suitability of the severe reforming method. Each full range reformate has an F_1 clear octane number within the range from 85 to 93. The heartcut from 75° C. to 160° C. from each reformate is subjected to severe reforming to provide an upgraded fraction having an F_1 clear octane number within the range from 102 to 105. Higher octane number of the severely reformed heartcut is necessary when the initial reformate is closer to the lower limit. In each case, a blend having an F_1 clear octane in the range from 100.1 to 101 is achieved.

The quantity of C_1-C_4 hydrocarbons produced at the high severity reforming is quite large, especially in relation to the quantity of hydrogen generated. In order to achieve nonregenerative conditions in the severe reforming stage, supplemental hydrogen must be introduced to preserve an adequately high hydrogen purity. The costs of maintaining a hydrogen to liquid hydrocarbon ratio such as 8 become excessive if the hydrogen purity is quite low, such as 33% by volume of recycle gas. By utilizing a hydrogen rich stream available in excess from the first stage reformer, and supplying it to the severe supplemental reformer at a rate equivalent to the gas production in the severe reformer while withdrawing an effluent gas stream at a rate equivalent to the gas production in the severe reformer, the recycle gas for the severe reformer can have an acceptable proportion of hydrogen. As indicated in connection with Examples II-V, supplemental hydrogen can be directed through the severe reformer if not operating in close proximity to the first stage reformer.

The hydrogen to liquid hydrocarbon unit ratio is thus maintained between 3 and 8. The total pressure is main-

tained within the range from 15 to 30 atmospheres. The reforming temperature is at least 480° C. but less than 550° C. Space rate is regulated from 1 to 3 volumes of heartcut per volume of catalyst per hour.

Obviously many modifications and variations of the invention as hereinbefore set forth may be made without departing from the spirit and scope thereof, and therefore only such limitations should be imposed as are indicated in the appended claims.

What is claimed is:

1. In the method in which the octane number of a liquid hydrocarbon is upgraded by treatment over a platinum catalyst under superatmospheric hydrogen pressure at conditions permitting continued operation for more than sixty days prior to catalyst regeneration, the improvement which consists of the combination of: fractionating a primary full range reformate of liquid hydrocarbons of 85 to 93 octane (F_1 clear) to provide a heartcut having an initial boiling point of at least 70° C., whereby normal hexane and lower boiling paraffins are substantially excluded, said cut having an end boiling point below 170° C., whereby polycyclic aromatics are substantially excluded; reforming said heartcut over supported platinum catalyst at severe conditions including hydrogen to liquid hydrocarbon unit ratio in the range from 3 to 8, space velocity from 1 to 3 volumes of liquid per volume of catalyst per hour, temperature in the range of 480° C. to 550° C., and pressure from 15 to 30 atmospheres; and blending the reformed heartcut with the remaining liquid forerun and bottoms components of the fractionated primary reformate to obtain a full range gasoline having an F_1 clear octane number greater than 100.
2. The method of reforming of claim 1 in which said primary reformate is one obtained by reforming a naphtha over a platinum catalyst under superatmospheric hydrogen pressure at conditions permitting continued operation for more than sixty days prior to catalyst regeneration in preparing a full range primary liquid reformate having an F_1 clear octane number within the range of 85 to 93, and in which said heartcut after severe reforming as defined has an F_1 clear octane number greater than 102.
3. The method of claim 2 in which at least a portion of the hydrogen-rich gas produced in reforming naphtha to an octane number from 85 to 93 is transferred to the inlet to the zone for severe reforming of said heartcut, and an approximately equal volume of gas is withdrawn from the effluent from said zone for reforming said heartcut, whereby the separate recycle gas streams are separately maintained at different hydrogen purities.

4. The method of claim 2 in which a naphtha is reformed to an octane number of about 90, a heartcut having a boiling point range from about 103° C. to about 163° C. is separated from such reformate, the heartcut is reformed at a temperature of about 535° C. at a space rate of about 3 volumes of liquid per volume of catalyst per hour at a pressure of about 20 atmospheres at a hydrogen to liquid hydrocarbon unit ratio of about 10 to provide a reformate, and such reformate is blended with the other fractions from the full range reformate to provide said full range gasoline having an F_1 clear octane number greater than 100.
